PLACE MAT OR THE LIKE

John E. Stengel, Bon Air, Va., assignor to Reynolds Metals Company, Richmond, Va., a corporation of Delaware

Filed July 16, 1965, Ser. No. 86,187

Term of patent 14 years

(Cl. D92—26)

FIG. 1 is a top plan view of a place mat showing my new design, the decorative ornamentation partially shown in full lines being completely repeated around the periphery as indicated in broken lines; and

FIG. 2 is an edge view thereof.

I claim:

The ornamental design for a place mat or the like, as shown and described.
